UNITED STATES PATENT OFFICE.

HERMAN H. PRETZEL, OF STILLWATER, MINNESOTA.

GREASE-GUN.

1,222,667.

Specification of Letters Patent. Patented Apr. 17, 1917.

Application filed May 19, 1915. Serial No. 29,287.

To all whom it may concern:

Be it known that I, HERMAN H. PRETZEL, a citizen of the United States, residing at Stillwater, in the county of Washington and State of Minnesota, have invented certain new and useful Improvements in Grease-Guns, of which the following is a specification:

My invention relates to improvements in 10 grease guns, designed particularly for forcing grease to different parts of automobiles, my improvements consisting particularly in means for allowing the gun to be more easily filled with grease than in the ordinary construction.

To this end my invention consists in the features of construction, combination, and arrangement of parts hereinafter described and claimed.

20 In the accompanying drawings forming part of this specification.

Figure 1 is a longitudinal section of a grease gun constructed in accordance with my invention; and

25 Fig. 2 is a central cross section of the same.

As shown in Fig. 2, the gun or casing K is preferably rectangular in cross section, the closure or slide B being fitted in an opening 30 in the top. The slide B is formed with tongues 1 and 2, which fit into grooves T and S in the side walls of the gun, the slide at its inner end being similarly formed with tongues to fit into similar grooves in the adjacent portion of the gun. The opposite end of the slide rests upon the end wall G of the gun and has anti-friction contact with said wall G, through the strip 1 held pressed against the slide by the springs J. C represents a piston or plunger through the central portion H of which is threaded a stem D. The piston C has anti friction connection with the slide B through the medium of the strip E held against the slide by the 40 springs F. The stem D is rotatable in the end of the wall G and provided with a handle M upon its outer end. The cover B is provided with a handle A.

The turning of the handle M will screw 50 the piston forwardly in the gun to force the grease out through the opening N. When it is desired to fill the gun the handle is turned to screw the piston rearwardly against the end wall G, the cover then being

slid outwardly until the stop 4 projecting from the underside of the cover strikes the piston C. The sliding back of the cover gives a large opening for the insertion of the grease.

I claim as my invention:

1. A grease gun comprising a casing having a discharge opening in an end wall and an entrance opening in a side wall through which the lubricant is inserted, a slideable closure for the side wall opening movable longitudinal of the casing, a plunger movable longitudinal in the casing for expelling the lubricant through the discharge opening thereof, and a stop arranged on the forward end of the closure in the path of the plunger 60 to engage the latter when the closure is moved to opened position for preventing further opening movement of the closure independent of the plunger whereby to always keep the space in the rear of the plunger 70 closed against ingress of the lubricant.

2. A grease gun comprising a casing having an end discharge opening and a side entrance opening, a closure for the side opening of the casing slideable from the rear 80 in a longitudinal direction to operative position, a plunger operable longitudinally in the casing across the side opening, and means carried by the closure and engageable with the plunger on opening movement of 85 said closure for holding the latter against uncovering the space in rear of said plunger.

3. A grease gun comprising a casing having a side entrance opening the surrounding edges of which are provided with grooves 90 extending over the rear end wall of the casing, a closure slideable over the end wall and interlocking in the grooves about the casing opening, a plunger slideable in the casing, and spring pressed strips on the casing end 95 wall and the plunger, said strips extending the width of the closure and exerting outward pressure on the closure at spaced points to firmly and evenly seat the closure on the walls of the grooves to provide a 100 grease-tight joint.

In testimony whereof I affix my signature in presence of two witnesses.

HERMAN H. PRETZEL.
